13 Claims. (Cl. 46—40)

1

This invention has reference to mechanical toys or models. The primary object of the invention is to provide an improved toy in the form of a mechanical load lifting device such as a crane, grab or scoop in which a number of operations necessary for the transference of a load from one place to another are carried out by means of a power source such as a spring or electric motor carried by the device, the operations being automatically effected in correct sequence and timing. A further object of the invention is to provide a device in the form of a toy or model as above set out in which the device includes a grab, bucket or pick up hook which is carried by a wheeled, tracked or other mobile structure, the sequence of operations including intermittent movement of the said structure, the pick up and discharge operations being performed whilst the structure is stationary, the device realistically simulating the normal action of the full size load lifting device.

The device according to the invention may be in the form of a stationary or fixed platform, but the invention further contemplates the employment of a mobile platform or member, the gearing from the main power source being coupled to the driving wheels or other members through a suitable mechanical device such as a cam and linkage actuated by the power source to impart an interrupted drive to the platform. It will be understood that the pick up and unloading operation occurs while the platform is stationary and the arrangement may be such that the platform movement is unidirectional or is reciprocatory.

Preferably, the power source consists of a clockwork motor but said power source could be an electric motor or a steam engine. The invention may be applied to a device in which the pick up member consists of a scoop, or said member may be a hook, or a grab bucket, i. e. a bucket consisting of two parts pivoted on a common center line, the parts opening and closing jaw fashion, the mechanism including means for opening and closing the jaws at the appropriate times in the cycle of operations, or said member could be an electro-magnetic device.

In order that a clear understanding of the invention may be obtained reference will now be made to the accompanying drawings illustrative of preferred forms of the invention, wherein:

Figure 1 is a side view of one form, wherein the cabin is mounted on a fixed base to turn on a vertical axis, the jib arm being shown in the loading or pick up position;

Figure 2 is a view looking from the left hand

2

side of Fig. 1 with the cabin turned through 90°. The arm where shown in full lines is in the discharging position and where shown in broken lines in the normal or carrying position;

5 Figure 3 is a plan view of the operating mechanism;

Figure 4 is a sectional view on the line IV—IV, Figure 3;

10 Figure 5 is a plan view showing an alternative mechanism for use with a mobile crane or the like wherein in addition to cabin turning and jib movement, the wheeled mounting platform is driven so as to move back and forth during appropriate periods in the cycle of operations;

15 Figure 6 is a sectional side view on the line VI—VI Figure 5;

Figure 7 is a fragmentary side view of an alternative mechanism in which the wheeled platform has an intermittent unidirectional movement imparted thereto;

20 Figure 8 is a sectional view on the line VIII—VIII Figure 7, and

Figure 9 is a side or general view which may represent either of the forms of the invention 25 utilising a wheeled platform.

Like reference numerals in the drawings indicate like or equivalent parts, and referring firstly to Figures 1 to 4, the construction illustrated includes a fixed base or supporting part 10 on which is mounted a cabin 11, said cabin housing the operating mechanism and being mounted for turning movement on the upper surface of the base 10, turning on the vertical spindle 12 with a ball race 13 concentric with the spindle 12 interposed between the underside of the cabin and the top of the platform.

The turning movement of the cabin on the vertical axis is obtained by means of a series of equally spaced holes 14 which series is arranged on an arc concentric with respect to the vertical turning axis of the cabin. The holes of the series are for engagement by the teeth of the pinion 15 driven by the shaft 16 as later described, whereby as the said pinion turns, the cabin turns about its vertical axis.

A clockwork or spring motor 17 is mounted in the cabin 11 on a horizontal axle 18. The operating mechanism is supported by the parallel side plates 19, 19, said mechanism including the axle 50 18, the main cog 20 and the gear train consisting of the pinions 21, 22, 23, 24, 25, 26, 27, and 28 arranged in coaxial pairs, the wheel 28 forming in combination with the pivoted member 29 an escapement which controls the speed of rotation 55 of the gear train. The lever 41 acts as brake.

for the motor. The turntable movement is controlled by the cam 30, whilst jib arm movement is controlled by the cam 31, both cams being fixedly mounted on the axle 18, which axle rotates in a clockwise direction, Fig. 4.

Dealing firstly with the cabin turning movement, an elbow lever 32 (Figs. 3 and 4) is mounted loosely on the axle 33, the lever having a turned over upper end 34, which runs on the edge of the cam 30, said lever being biased by a spring 35 so that the end 34 is maintained against the edge of the cam 30 during its full rotation. The end of the horizontal arm of the lever has a slot 36 therethrough in which a pin 37 on the cog 38 engages, said cog being carried by a spindle 39 and meshing with a cog 40 carried by the spindle 16. The spindle 16 projects beyond the plate 19, at one side (Fig. 3) and has the pinion 15 mounted thereon the teeth of which pinion are shaped to engage in the arcuately arranged row of holes 14. Starting at the position shown in Figs. 1 and 4, with the axle 18 rotating, the cam 30 during its rotation rocks the lever 32, which movement through the slot and pin coupling 36, 37, turns the cog 38 and thereby turns the pinion 15 through the cog 40. The rise of the cam 30 is sufficient to give a turning movement of the cabin of approximately 90°, whereupon the arm end 34 rides on the cam edge part 30a which is arcuate with respect to the axis of rotation of the cam so that the lever 32 is stationary and consequently the cabin does not turn until the end 34 commences to ride on the fall of the said cam. The movement of the jib arm 42 occurs whilst the cabin is stationary, said jib arm movement being controlled by the cam 31 and linkage. The jib arm is pivoted by a pin 44 on the transverse axis of the cabin being urged by the coil spring 45 around the pin 44 into its maximum up-swing position. The linkage comprises two arms 46, 47, pivoted together at 48 with the one arm 46 at its lower end loose on the spindle 33, the other arm 47 being pivoted to the one side of the jib arm. In the position shown in Figs. 1 and 4, the arm 42 is lowered to its maximum extent and as the cam 31 rotates, the pin 49 on the arm 46 (which pin bears on the edge of cam 31), rides on the cam surface resulting in the lifting of the jib arm.

The pick up bucket 50 is connected to the jib arm by a cord 51 anchored at one end at 52, then passing around the pulley 53, back and over the double grooved pulley 54, around the bucket pulley 55, back over the pulley 54, and is anchored at its other end at 56. A second cord 57 is connected at one end to the rear of the bucket, and passes over the pulley 58, and its other end is connected to the upper end of the lever 59. Said lever 59 is pivoted in a yoke 60 fixed to the motor cross bar 61, and the inner face of the gear 20 has a pin 62 thereon. With this arrangement, for each revolution of the axle 18, i. e. once every cycle of operations, the lever 59 is rocked in counterclockwise direction Fig. 4 by the pin 62 so that the rear end of the bucket is raised to tip said bucket.

The mechanism in the first embodiment shown is timed to operate as follows:

Assuming the parts are in the position shown in Figs. 1, 3 and 4, then the bucket is in its loading position. As the axle 18 rotates, the jib arm first swings upwardly, under the action of the cam 31 and its associated linkage, and the cam 30, through its lever 32 and gear train and arcuate rack 14 turns the cabin through approximate-

ly 90° to the position shown in Fig. 2. It will be seen that the jib arm rises prior to the cabin turning movement i. e. into the position shown in broken lines. After the cabin has stopped 5 turning, continued movement of the cam 31 results in movement of linkage 46, 47 to lower the jib arm, and when lowered, the pin 62 on the gear wheel 20 has moved into a position to rock the lever 59, so raising the rear of the bucket or 10 scoop and tipping same, the parts being in the position shown by full lines Fig. 2.

Referring now to the construction which is illustrated in Figs. 9, 5 and 6, and in particular to the latter two figures, the cabin is mounted on a vertical axis for turning on the platform 16a which platform comprises a chassis structure mounted on two pairs of wheels 63, 63, and 64, 64, the rear pair 64 being driven to impart a forward and back movement to the chassis. The wheels may be coupled by an endless track or band at each side. The gear wheel 20 in this case is formed on its one face with a cam ring 65, and also mounted within the ring and driven by the axle 18 is the cabin turning cam 30. This latter cam is coupled through the elbow arm 32a and pin 34a to a crank 66, the end of which engages in the slot 36a, whereby on the rocking of the arm, the arcuate contrate gear wheel 67 is turned, said gear being coupled to a cog 68 on a vertical spindle 69. Beneath the cabin base is the gear wheel 70 also mounted on the spindle 69, said wheel 70 meshing with the rack 70a concentric with respect to the vertical cabin mounting spindle 12.

The spindle 12 in this embodiment has a bevel wheel 71 on its upper end and a similar wheel 72 at its lower end, which wheel 72 meshes with the bevel wheel 73 keyed to the shaft 64a.

The drive to the bevel wheel 71 is through the bevel wheel 74 mounted on the spindle 75 to which drive is imparted by the cog 76 mounted on said spindle 75. The cam ring 65 is utilised to control the drive to the cog 76, so that said cog can be stationary (during the major part of the jib arm movement) or turn in one direction for forward chassis movement, or turn in the opposite direction for rearward chassis movement. This reverse movement may be imparted by any suitable means such as a dog clutch mechanism, but preferably the movement is imparted by the pair of pinions 77, 77a mounted on a cradle 78 freely pivoted on the spindle 75, the cradle being rocked by the cam so that both pinions 77, 77a can be free from engagement with pinions 22, 24 respectively in the gear train which in this case mesh and are identical to travel at the same peripheral speed, or pinion 77 can mesh with pinion 22 or (as shown in Fig. 6) pinion 77a meshes with pinion 24.

The coupling between the cam ring 65 and the cradle is through a cranked arm 79 having a pin 80 at its upper end to engage the cam ring which arm 79 is also coupled to said cradle by the pin 81 on the cradle and slot 82 in the arm end, the arm 79 being pivoted to the plate 19 at 83. The said pin 80 is constrained to follow the outward curves of the cam track 65 to couple the drive to, and uncouple the drive from the wheels, by virtue firstly of the path formed between said curve and the cam 30, and secondly by virtue of the path formed between the abutment 84 and the said curve. In this embodiment the gear train comprises the pinions 21, 22, 24, 25, 26, 27 and 28, the speed being controlled by the escapement 29. It will be clear that pinions 22

and 24 travel at the same speeds but in opposite directions.

The mechanism for operating the jib arm is conveniently the same as described with reference to the first embodiment, and in the position shown in Figs. 5 and 6, the drive is coupled to the rear wheels, the pin 80 being in the operative section between abutment 84 and cam track so that the platform is moving forwardly, until the pin 80 leaves the depressed cam part whereupon the drive to the wheels is broken. It will be understood that the drive to the wheels is coupled up only when the pin 80 is in the one or other of the two "operative" sections above defined, that is to say, the platform is stationary when the pin 80 rides on the two sections of the cam which are concentric with its center of rotation or plain sections. As the pin 80 commences to ride on its approaching first plain section, and during the period it rides on this section, the jib arm is lowered by the cam and pin arrangement 31, 49 and associated levers, as described with reference to the previous embodiment. The cabin remains stationary with the jib forwardly extending, when the said jib is moving, the cam 31 being located on its shaft 18 in such an angular position that the jib arm rises before the pin 80 runs on its next operative cam part adjacent the larger radiussed part of cam 30.

When the gear to the rear wheels is next coupled up, the structure moves rearwardly, until the pin leaves the operative cam part aforesaid. The cabin is now turned on its axis, as the pin 34a now leaves the smaller radiussed part of the cam 31 and on or just before the cabin completes its movement aforesaid (the pin 34a now riding on the larger radiussed part of its cam 30), the jib arm is lowered. In this case, at the completion of the lowering action the scoop is tipped and the jib arm then rises, whereupon the cabin is returned as the pin 34 is now riding on its cam section from the larger radiussed part to the smaller radiussed part, and at or about the instant cabin stops and the pin 34a commences to ride on its smaller radiussed part the pin 80 enters the operative cam part between the cam and the abutment 84.

It will be understood however, that the cam and actuating members may be arranged to produce any desired sequence of operations.

In the modification illustrated in Figs. 5, 7 and 8, an arrangement is shown wherein intermittent forward movement is imparted to the wheeled platform. In this case, the outer face of the gear 20 is formed as a cam track 85, and a rod 86, each end of which is bent as at 87, 88, is secured to the plate 19 by brackets 89, 89, whereby said rod can be turned on its axis. The end 87 projects upwardly to engage the cam track 85, whilst the end 88 is coupled to the groove 90 formed by a boss between the flange 91 and the pinion 92. The said pinion is loose on the shaft 75, on which the bevel gear or pinion 74 is keyed, the coupling between pinions 74, 92 being made by the teeth 93, 93a.

When the arm end 87 rides on the thick part of the cam rim, the pinion 92 is in the position shown in Fig. 8 the teeth 93, 93a, being disengaged. When however, the cog 20 has turned so that the thin part 85a of the cam rim is engaged by the arm end 87, then the pinion 92 is slid towards the bevel 75 by spring pressure so that the teeth 93, 93a are in engagement.

The jib arm in the constructions illustrated carries a pick-up bucket or scoop, but it will be

clear from the foregoing description with reference to the drawings that other forms of pick-up devices could equally well be used. Thus, a two part grab could be provided, the cord 57 being connected to the pivoted together parts so that the rocking of the lever 59 by the pin 62 moves the cord to open and close the grab at the appropriate points in the cycle of operations.

I claim:

1. Toy or model mechanical load lifting device comprising a base, a cabin pivoted on the base about a vertical axis, a jib arm fulcrumed on the cabin, a pick-up device carried by the jib arm, a power source on the cabin, operable means on the cabin cooperating with the base and rotating the cabin on the base from one position to a second and back, second means driven by the power source and operating the first means for cabin rotation from the first to the second position and back, third means driven by the power source and swinging the jib arm up and down while the cabin is in its first position and swinging the jib arm down and up while the cabin is in its second position, fourth means lowering the pick-up device relative to the jib arm during the upward swing thereof and raising the pick-up device relative to the jib arm during the down swing thereof, and fifth means driven by the power source and lifting the rear end of the pick-up means when the jib arm is in lowered position in the second cabin position.

2. A toy or model mechanical load lifting device such as a grab or crane comprising a supporting platform, a cabin mounted on a vertical pivot axis on said platform, a power source carried by said cabin, a jib arm carried by said cabin and mounted for swinging raising and lowering movement thereon, gearing between said power source and a drive between the cabin and platform for effecting the turning of the cabin on its pivot axis, cam mechanism actuated by the power source and operatively coupled to the said gearing to effect the turning of the cabin from one position to a second position, and a second cam mechanism actuated by the said power source, which second mechanism is operatively coupled to the jib arm to effect raising and lowering thereof, the two cam mechanisms being timed so that the major portion of the jib movement to effect load pick up and discharge is obtained when the cabin is in one or other of its stationary positions.

3. Toy or model mechanical load lifting device comprising a supporting platform, a cabin mounted on a vertical turning axis on said platform, a jib arm carried by said cabin on a horizontal pivot axis, a power source carried by the cabin, a main spindle in the cabin driven by said power source, a cam on said spindle, a linkage coupling said cam to a pinion, which pinion is coupled to a radial driving rack on the platform, said cam having two operative sections for cabin turning movement from a pick up position to a discharge position, with non-operative sections therebetween, a jib arm operating cam on said spindle, a linkage coupling said jib arm operating cam to the jib arm, said jib arm operating cam having two operative sections for jib arm lowering and raising during non-cabin turning periods, with a pick up device carried by said jib arm.

4. Toy or model mechanical load lifting device comprising a supporting platform, a cabin mounted on a vertical turning axis on said platform, a jib arm carried by said cabin on a horizontal pivot axis, a power source carried by the

cabin, a main spindle in the cabin driven by said power source, a cam on said spindle, a linkage coupling said cam to a pinion, which pinion is coupled to a radial driving rack on the platform, said cam having two operative sections for cabin turning movement from a pick up position to a discharge position, with non-operative sections therebetween, a jib arm operating cam on said spindle, a linkage coupling said jib arm operating cam to the jib arm, said jib arm operating cam having two operative sections for jib arm lowering and raising during non-cabin turning periods, with a pick up device carried by said jib arm and means driven by the power source for operating the pick up device during jib arm movement.

5. Toy or model mechanical load lifting device comprising a supporting platform, a cabin mounted on a vertical turning axis on said platform, a jib arm carried by said cabin on a horizontal pivot axis, a power source carried by the cabin, a main spindle in the cabin driven by said power source, a cam on said spindle, a linkage coupling said cam to a pinion, which pinion is coupled to a radial driving rack on the platform, said cam having two operative sections for cabin turning movement from a pick up position to a discharge position, with non-operative sections therebetween, a jib arm operating cam on said spindle, a linkage coupling said jib arm operating cam to the jib arm, said jib arm operating cam having two operative sections for jib arm lowering and raising during non-cabin turning periods, with a pick up device carried by said jib arm and means driven by the power source for operating the pick up device during jib arm movement, said pick up operating means comprising a pulley guided cord connected at one end to the pick up device and at the other end to the cabin, the power source coupled to said cord by a linkage connected to the power source, which linkage is operated during stationary periods of the cabin.

6. A toy or model mechanical load lifting device such as a grab or crane comprising a supporting platform, a cabin mounted on a vertical pivot axis on said platform, a power source carried by said cabin, a jib arm carried by said cabin and mounted for swinging raising and lowering movement thereon, gearing between said power source and a drive between the cabin and platform for effecting the turning of the cabin on its pivot axis, cam mechanism actuated by the power source and operatively coupled to the said gearing to effect the turning of the cabin from one position to a second position, and a second cam mechanism actuated by the said power source, which second mechanism is operatively coupled to the jib arm to effect raising and lowering thereof, the two cam mechanisms being timed so that the major portion of the jib movement to effect load pick up and discharge is obtained when the cabin is in one or other of its stationary positions, a wheeled mounting for said platform, gearing between the power source, and the wheels for rotating same, and means actuated by the power source for interrupting the drive during cabin turning and jib arm movement.

7. Toy or model mechanical load lifting device as claimed in claim 6, in which the drive to the wheels is unidirectional.

8. Toy or model mechanical load lifting device as claimed in claim 6, in which the drive to the wheels is reciprocatory.

9. Toy or model mechanical load lifting device comprising a supporting platform, a cabin

5. mounted on a vertical turning axis on said platform, a jib arm carried by said cabin on a horizontal pivot axis, a power source carried by the cabin, a main spindle in the cabin driven by said power source, a cam on said spindle, a linkage coupling said cam to a pinion, which pinion is coupled to a radial driving rack on the platform, said cam having two operative sections for cabin turning movement from a pick up position to a discharge position, with non-operative sections therebetween, a jib arm operating cam on said spindle, a linkage coupling said jib arm operating cam to the jib arm, said jib arm operating cam having two operative sections for jib arm lowering and raising during non-cabin turning periods, with a pick up device carried by said jib arm, means driven by the power source for operating the pick up device during jib arm movement, and a wheel drive control cam on said main spindle, which cam is coupled through linkage to an interrupting gear to the wheels.

10. Toy or model mechanical load lifting device comprising a supporting platform, a cabin mounted on a vertical turning axis on said platform, a jib arm carried by said cabin on a horizontal pivot axis, a power source carried by the cabin, a main spindle in the cabin driven by said power source, a cam on said spindle, a linkage coupling said cam to a pinion, which pinion is coupled to a radial driving rack on the platform, said cam having two operative sections for cabin turning movement from a pick up position to a discharge position, with non-operative sections therebetween, a jib arm operating cam on said spindle, a linkage coupling said jib arm operating cam to the jib arm, said jib arm operating cam having two operative sections for jib arm lowering and raising during non-cabin turning periods, with a pick up device carried by said jib arm, means driven by the power source for operating the pick up device during jib arm movement, and a wheel drive control cam on said main spindle, which cam is coupled through linkage to an interrupting gear to the wheels.

45. 11. Toy or model mechanical load lifting device comprising a supporting platform, a cabin mounted on a vertical turning axis on said platform, a jib arm carried by said cabin on a horizontal pivot axis, a power source carried by the cabin, a main spindle in the cabin driven by said power source, a cam on said spindle, a linkage coupling said cam to a pinion, which pinion is coupled to a radial driving rack on the platform, said cam having two operative sections for cabin turning movement from a pick up position to a discharge position, with non-operative sections therebetween, a jib arm operating cam on said spindle, a linkage coupling said jib arm operating cam to the jib arm, said jib arm operating cam having two operative sections for jib arm lowering and raising during non-cabin turning periods, with a pick up device carried by said jib arm, means driven by the power source for operating the pick up device during jib arm movement, and a wheel drive control cam on said main spindle, which cam is coupled through linkage to an interrupting gear to the wheels, said interrupting drive comprising a clutch.

50. 11. Toy or model mechanical load lifting device comprising a supporting platform, a cabin mounted on a vertical turning axis on said platform, a jib arm carried by said cabin on a horizontal pivot axis, a power source carried by the cabin, a main spindle in the cabin driven by said power source, a cam on said spindle, a linkage coupling said cam to a pinion, which pinion is coupled to a radial driving rack on the platform, said cam having two operative sections for cabin turning movement from a pick up position to a discharge position, with non-operative sections therebetween, a jib arm operating cam on said spindle, a linkage coupling said jib arm operating cam to the jib arm, said jib arm operating cam having two operative sections for jib arm lowering and raising during non-cabin turning periods, with a pick up device carried by said jib arm, means driven by the power source for operating the pick up device during jib arm movement, and a wheel drive control cam on said main spindle, which cam is coupled through linkage to an interrupting gear to the wheels, said interrupting drive comprising a reverse gear having a neutral position, and the wheel drive control cam operates said gear to effect forward, reverse and stop of the platform.

75. 12. Toy or model mechanical load lifting device comprising a supporting platform, a cabin mounted on a vertical turning axis on said platform,

form, a jib arm carried by said cabin on a horizontal pivot axis, a power source carried by the cabin, a main spindle in the cabin driven by said power source, a cam on said spindle, a linkage coupling said cam to a pinion, which pinion is coupled to a radial driving rack on the platform, said cam having two operative sections for cabin turning movement from a pick up position to a discharge position, with non-operative sections therebetween, a jib arm operating cam on said spindle, a linkage coupling said jib arm operating cam to the jib arm, said jib arm operating cam having two operative sections for jib arm lowering and raising during non-cabin turning periods, with a pick up device carried by said jib arm, means driven by the power source for operating the pick up device during jib arm movement, and a wheel drive control cam on said main spindle, which cam is coupled through linkage to an interrupting gear to the wheels, said interrupting drive comprising a reverse gear having a neutral position, and the wheel drive control cam operates said gear to effect forward, reverse and stop of the platform, said reverse drive comprising a pair of pinions carried by a rockable cradle to which movement is imparted by an arm actuated by the cam, said pinions meshing with a common pinion on a shaft coupled through bevel gears to the vertical shaft, the said cradle taking up one of three positions as determined by the cam, one said position meshing one pinion of the pair with a wheel in the gear train to turn the common pinion in one direction, a second position meshing the other pinion of the said pair with another oppositely rotating wheel in the gear train to turn the common pinion in the opposite direction, the third position breaking the mesh of both said pinions from the gear train.

13. Toy or model load lifting device comprising

6 a wheeled platform, a cabin mounted on said platform on a vertical spindle, a power source carried by the cabin, gearing driven by said power source and coupled to the wheels, a cam driven by the power source and operatively coupled to a reverse and interrupting gear in the said gearing, a jib arm carried by the cabin, a cam driven by the power source and operatively coupled to the jib arm through mechanism for raising and lowering said jib arm, a cabin control cam driven by the power source and operatively coupled to a gear for effecting the turning of the cabin from a pick up position to a discharge position, said cam for controlling the reverse gear moving the cabin forwardly to the pick up position, said cam for the jib arm movement lowering the jib for the pick up operation in the forward position, said cam for controlling the reverse gear coupling up the said gear for reversal after pick up operation, said cabin control cam effecting cabin turning movement in the rearward position, the jib movement cam lowering the jib arm for discharge in the rearward position of the cabin and subsequently effecting the rising of the jib arm, said cabin control cam returning the cabin, in which position said gear controlling cam couples up the drive for forward movement of the platform.
